DESIGN FOR A LAMP-CHIMNEY.

The Schedule referred to in these Letters Patent and making part of the same.

To all whom it may concern:

Be it known that I, GEORGE W. MOYERS, of Gordonsville, in the county of Orange and State of Virginia, have invented a new and valuable Design for Lamp-Chimneys; and I do hereby declare that the following is a full, clear, and exact description of the construction and operation of the same, reference being had to the annexed drawing making a part of this specification, and to the letters and figures of reference marked thereon.

Figure 1 of the drawing is a representation of my lamp-chimney in perspective.

Figure 2 is a top view of the same.

My design is for lamp-chimneys, and may be described as a three-sided chimney, or one having three reflectors, each of which is opposite to a corner, as shown in the drawing.

I claim the design for a lamp-chimney, herein shown and described.

In testimony that I claim the above, I have hereunto subscribed my name in the presence of two witnesses.

GEO. W. MOYERS.
